DESIGN FOR A SINGLE RUNNER SLED

William Flajole, Detroit, Mich., assignor of one-half to Irving Goldsmith, Detroit, Mich.

Application March 15, 1946, Serial No. 127,536

Term of patent 14 years

(Cl. D34—15)

To all whom it may concern:

Be it known that I, William Flajole, a citizen of the United States, residing at Detroit, in the county of Wayne and State of Michigan, have invented a new, original, and ornamental Design for a Single Runner Sled, for which the following is a specification, reference being had to the accompanying drawing, forming part thereof, in which:

Fig. 1 is a perspective view of the sled; and
Fig. 2 is another perspective view thereof showing my design.

I claim:

The ornamental design for a single runner sled, substantially as shown.

WILLIAM FLAJOLE.
